UNITED STATES PATENT OFFICE.

JAMES CARLTON HAMMOND, OF JACKSONVILLE, FLORIDA.

PORTABLE BATHHOUSE.

1,385,615.

Specification of Letters Patent. Patented July 26, 1921.

Application filed July 22, 1920. Serial No. 398,232.

To all whom it may concern:

Be it known that I, JAMES CARLTON HAMMOND, a citizen of the United States, residing at Jacksonville, in the county of Duval and State of Florida, have invented a new and useful Portable Bathhouse, of which the following is a specification.

This invention relates to a portable enclosure or tent especially designed for use as a bath house, one of the objects of the invention being to provide a structure of this character which can be easily set up for use, does not require guy ropes or stays and which provides a clear space within the inclosure free of central supports.

A further object is to provide a structure of this character which, when not in use, can be folded into a compact bundle and easily carried from place to place.

Another object is to provide a foldable top frame having simple and efficient means for fastening it in extended position.

With the foregoing and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is a vertical transverse section through the structure.

Fig. 2 is a bottom plan view of the central portion of the top of the structure.

Fig. 3 is a plan view of a portion of the top frame of the structure.

Fig. 4 is an elevation of the meeting ends of the sections of one of the supports.

Fig. 5 is an elevation showing the opposite side of the part shown in Fig. 4.

Fig. 6 is a view partly in section and partly in elevation showing the engaged portions of one of the supports and the top frame.

Referring to the figures by characters of reference 1 designates the upper member of a support, the same having its upper end reduced to form a stud 2 while its lower end is connected, by a hinge 3 to the lower member 4 of the support. The lower end of

the member 4 is pointed as at 5 to form a stake adapted to be forced into the ground. Connected to the member 1 at that side opposite the hinge 3 is a fastening device 60 which can be in the form of a hook 6 adapted to engage an eye 7 connected to the upper portion of the lower member 4.

The top frame of the device includes a central block 8 preferably having four sides 65 and hingedly connected to each of these sides is a radial arm 9 to the outer end of which is secured an eye 10. The hinges for connecting the arms 9 to the block 8 have been indicated at 11. To the upper surface 70 of one of the arms 9 a holding strip 12 may be pivotally connected, as indicated at 13, this strip being of sufficient length to extend across the block 8 and being provided, near its free end, with a transverse slot 14 adapted to receive a stud 15 extending from one of the arms 9. Thus it will be seen that the two opposed arms connected by this strip 12 will be held extended. Upward folding or buckling of the frame is thus prevented. 80

The covering of the device constituting the present invention is preferably made in a single piece and consists of the angular top portion 16, the connected walls 17 and the curtains or flaps 18 which constitute the closures for the open side of the device. These curtains are adapted to be held together by buttons 19 or any other suitable means. 85

When the device is not in use the supports made up of the sections 1 and 4 are folded together and the arms 9 are also folded together, these supports and arms being rolled up on the fabric making up the top and walls of the device.

When it is desired to set up the device 95 for use the arms 9 are swung outwardly and the strip 12 is placed in engagement with the stud 15. The supports made up of the sections 1 and 4 are then positioned with the studs 2 within the eyes 10 and the points 100 or stakes 5 are forced into the ground. The covering is then placed over the frame thus produced and will therefore form a dressing room or bath house of ample proportions.

It is to be understood that any suitable 105 arrangement of eyes 20 can be provided on the sections 1, these eyes being adapted to support garment hooks or the like, as shown at 21.

A device such as described can be easily 110 collapsed and carried and is therefore especially useful for tourists.

What is claimed is:

1. A portable structure including a central block, arms hingedly connected to the respective sides of the block and foldable together, fastening means movably connected to one of the arms and extending across the top face of the block and detachably connected to the opposed arm, said block being held by gravity in abutment with the inner ends of the arms when the arms are extended, supports for the arms, means detachably engaging the supports for holding them extended, said supports having pointed ground engaging ends, a one piece fabric housing having a top portion bearing downwardly on the block and arms, wall portions extending along and between the supports, and flaps between two of the supports.
- 10 15
2. A portable structure including a central block, arms hingedly connected to the respective sides of the block and foldable together, fastening means movably connect-

ed to one of the arms and extending across the top face of the block and detachably connected to the opposed arm, said block being held by gravity in abutment with the inner ends of the arms when the arms are extended, supports for the arms, means detachably engaging the supports for holding them extended, said supports having pointed ground engaging ends, a one piece fabric housing having a top portion bearing downwardly on the block and arms, wall portions extending along and between the supports, and flaps between two of the supports, and means for engaging the flaps to hold them closed.

In testimony that I claim the foregoing as my own, I have hereto affixed my signature in the presence of two witnesses.

JAMES CARLTON HAMMOND.
